INVENTOR.

Solomon G. Schulz,

BY

Geo. F. Kimmel

ATTORNEY.

UNITED STATES PATENT OFFICE.

SOLOMON G. SCHULZ, OF PARKSTON, SOUTH DAKOTA.

TIE HITCH.

Application filed December 18, 1928. Serial No. 325,771.

This invention relates to a tie hitch and has for its primary object to provide, in a manner as hereinafter set forth, a device for adjustably hitching two or more horses together and maintaining them a predetermined distance apart, whereby as many horses as desired may be driven abreast without danger of the horses crowding together and becoming unmanageable.

10 A further object of the invention is to provide a device as aforesaid, by means of which four or more horses may be effectively hitched abreast in a manner to provide for the driving of the horses with one pair of lines.

With the foregoing and other objects in view, the invention consists of the novel construction, combination and arrangement of parts as hereinafter more particularly described, and as illustrated in the accompanying drawings wherein is shown a preferred embodiment of the invention, but it is to be understood that such description and drawings are to be taken as illustrative and that 25 the invention is intended to be limited only by the scope of the claims hereunto appended.

In the accompanying drawings in which like numerals are employed to designate like parts throughout the same:

Figure 1 is an elevation of a tie hitch constructed in accordance with this invention.

Figure 2 is a view similar to Figure 1 shown partly in section.

Figure 3 is a top plan of the embodiment shown in Figure 1.

Figure 4 is a section taken on line 4—4 of Figure 2.

Figure 5 is an enlarged, fragmentary, sectional elevation, showing the latching member in operative position in full lines and in inoperative position in dotted lines.

Referring to the drawings in detail, the numeral 1 designates an elongated, hollow member having a tapered end 2 to which is secured a chain 3, which is provided with a snap 4 by means of which the member 1 may be secured in position. Adapted to slide within the member 1 is an elongated member 5 which is preferably formed of a tough wood to provide a certain degree of resiliency without breaking. Secured to one end 50 of the member 5 is a chain 6 which is pro-

vided with a snap 7 by means of which the member 5 may be secured in position. The 55 member 5 is formed with an elongated, longitudinally extending groove 8, in the bottom wall of which is formed a plurality of spaced recesses 9.

Secured to the outer face of the hollow member 1, by means of a suitable holdfast device 10, is an elongated, resilient element 11 having an inherent tendency to swing its free end away from the member 1. Depending from the lower face of the element 11 is a lug 12 which normally extends slightly 60 into an opening 13 formed in the member 1, in spaced relation to the inner end thereof. Adjacent the opening 13, a supporting element in the form of a steeple 14 is secured 65 to the member 1.

Pivottally mounted on the steeple 14 is a latch member 15, substantially in the form of a bell crank, and comprising a long arm 16 and a short arm 17. The arms 16 and 17 are disposed at an angle to each other of slightly more than 90° and with the member 15 disposed in latching position, the free ends of the arms 16 and 17 bear against the upper face of the resilient element 11. In 70 this position, the short arm 17 is slightly off center with respect to the vertical plane of the steeple 14 and the resilient element 11 is forced downwardly with its inner face almost in contact with the member 1. Only 75 sufficient play is left between the resilient element 11 and member 1 to permit the short arm 17 to be swung past center when the latch member 15 is swung to inoperative position as shown in dotted lines in Figure 80 5. With the latch member 15 in inoperative position, the inherent resiliency of the member 11 forces the same upwardly into the position illustrated in dotted lines in Figure 90 5.

With the latch member 15 in inoperative position, the free end of the lug 12 is positioned within the groove 8 in spaced relation to the bottom wall thereof. With the lug 12 so disposed, any relative rotary movement 95 between the members 1 and 5 is prevented. In this position a free longitudinal movement is permitted between the members 1 and 5 in order that the recesses 9 may selectively be brought into registry with the opening 13 formed in the member 1. With 100 105

the opening 13 in registry with one of the recesses 9, the latch member 15 may be moved to operative position, which forces the lug 12 into such recess, by means of which the members 1 and 5 are locked against relative longitudinal movement.

Preferably the members 1 and 5 are each of about five feet in length and the recesses 9 are disposed about six inches apart. Also 10 the ends of the grooves 8 are disposed about six inches from the ends of the member 5. With these proportions the members 1 and 5 may be locked in selective positions to vary the entire length of the device from approximately 15 five and one-half feet to nine feet. The snaps 4 and 7 are adapted for connection with the bridles of adjacent horses and the flexibility of the chains 3 and 6 provides for free movement of the horses' 20 heads within the limits of the lengths of the chains.

It is to be noted that relative rotary movement between the members 1 and 5 is prevented whether the latch member is in operative or inoperative position due to the fact that the lug 12 projects into the groove 8 at all times. Should the latch member 15 inadvertently be moved to inoperative position, the members 1 and 5 would be prevented from becoming separated by the engagement of the lug 12 with the inner wall 25 of the groove 8.

It is thought that the many advantages of a tie hitch in accordance with this invention 30 will be readily apparent, and although the preferred embodiment of the invention is as illustrated and described, yet it is to be understood that various changes in the details of construction may be made which fall 35 within the scope of the invention as defined in the appended claims.

What I claim is:

1. A tie hitch comprising, an elongated hollow member formed with an opening 40 through its wall and having one end adapted for connection with a bridle, an elongated 45 slideable member having one end inserted in the hollow member and having its other end adapted for connection with a bridle, said 50 slideable member being formed with a longitudinal groove, a resilient element secured to the hollow member and having a lug normally 55 extending into said groove, whereby relative rotary movement between said members is prevented, means for depressing and latching said element to force the lug inwardly with respect to the hollow member, and spaced means provided on the slideable member for selective engagement 60 with the lug when the latter is forced inwardly, to prevent relative longitudinal movement between said members.

2. A tie hitch comprising, an elongated hollow member formed with an opening 65 through its wall and having one end adapted

for connection with a bridle, an elongated slideable member having one end inserted in the hollow member and having its other end adapted for connection with a bridle, said slideable member being formed with a longitudinal groove and with a plurality of spaced recesses in the bottom wall of the groove, a resilient element secured to the hollow member and having a lug extending through said opening and into said groove whereby relative rotary movement between said members is prevented, and means for depressing and latching said resilient element to force the lug into engagement with the walls of one of said recesses to prevent relative longitudinal movement between said members.

3. A tie hitch comprising, an elongated hollow member having one end adapted for connection with a bridle, said member being formed with an opening through its wall, 85 an elongated slideable member having one end inserted in the hollow member and having its other end adapted for connection with a bridle, a resilient element secured to the hollow member and having a lug extending into said opening, means for depressing and latching said element to force the lug inwardly with respect to the hollow member, and spaced means provided on the slideable member for selective engagement 90 with the lug when the latter is forced inwardly, to prevent relative movement between said members, said depressing and latching means including a supporting element carried by the hollow member, and a 95 latch member pivotally mounted on said supporting element, said latch member having a pair of angularly disposed arms for seating on the outer face of said resilient element.

4. A tie hitch comprising, an elongated hollow member having one end adapted for connection with a bridle, an elongated slideable member having one end inserted in the hollow member and having its other end adapted for connection with a bridle, said slideable member being formed with a longitudinal groove, a resilient element secured to the hollow member and having a lug normally 110 extending into said groove, means for depressing and latching said resilient element to force the lug inwardly with respect to the hollow member, and spaced means provided on the slideable member for selective engagement with said lug when the latter is forced inwardly for locking said members together.

5. A tie hitch comprising, an elongated hollow member formed with an opening through its wall, an elongated slideable member having one end inserted in the hollow member and formed with a longitudinally extending groove, a resilient element secured to the hollow member and having a lug extending through said opening and into said 125

groove, means for depressing and latching said resilient element to force the lug inwardly with respect to the hollow member, spaced means provided on the slideable member for selective engagement with the lug when the latter is forced inwardly, to prevent relative movement between said mem-

bers, and flexible means on the outer ends of said members for connection with a pair of bridles.

In testimony whereof, I affix my signature hereto.

SOLOMON G. SCHULZ.
